UNITED STATES PATENT OFFICE.

CHARLES W. RYDER AND FRANKLIN ORTH, OF BURLINGTON, VERMONT.

ELECTRIC-CAR SIGN AND SIGNAL.

No. 838,586.

Specification of Letters Patent.

Patented Dec. 18, 1906.

Application filed April 8, 1905. Serial No. 264,536.

To all whom it may concern:

Be it known that we, CHARLES W. RYDER and FRANKLIN ORTH, citizens of the United States, residing at No. 163 South Union street, in the city of Burlington, in the county of Chittenden and State of Vermont, have invented a new and useful Improvement in Electric-Car Signs and Signals, of which the following is a specification.

10 The objects of our improvement are, first, to provide a sign upon electric cars to give the names of places and routes; second, to provide signals of different-colored lights, and, thirdly, to provide means to turn the 15 electric current on or off from the different compartments of the sign, hereinafter described, and adapted to be placed upon an electric car.

Our invention also relates to improvements in illuminated signals and street-car signs by which a series of signals and inscriptions may be disclosed during the day and night time and be interchanged at will, though it is evident that the sign can be used 25 independent of the car.

It is the object of our present invention to provide a sign which may be easily mounted on the end or sides of a car in position to display different-colored signals and inscriptions 30 and have these interchangeable at will by means of actuating mechanism arranged within reach of a motorman or conductor.

Further objects of this invention are to provide means by which a many-sided sign 35 may be rotated or reversed at suitable intervals, so that any inscription or set of signals may be brought into position to be read from the street; to provide means by which the sign may be locked or held firmly and steadily in place until it is desired to change the 40 position of the sign for presenting another inscription or set of signals to view, and also to prevent the accidental rotation of the sign and signals by any jar of the car, as in cross- 45 ing switches; to provide means by which a current of electrical energy may be supplied to incandescent lights within the revolving or reversing sign and signals in a manner to avoid interfering with the rotating or reversing 50 of said sign and signals and to supply this current of electrical energy in such a way as to be continuous or not interrupted or interfered with by or during the time of rotating or reversing the sign and signals, so

that there is no liability of sparking or arcing 55 or of the lamps being temporarily extinguished due to the vibration or the reversal of the sign and signals.

Our invention comprises, generally speaking, a many-sided box of two or more separate compartments—one or more for the inscriptions and two for the signals—and so arranged that they can be controlled or lighted independently and separately. Each sign is equipped with transparent or translucent 60 panes, which are provided with suitable inscriptions in the sign-compartments and of suitable color in the signal-compartments. Furthermore, these panes are secured removably within the frames, so that the inscription 65 may be removed and a pane bearing a fresh inscription or an inscription of a different character supplied or a pane of different color put in the signal-sections. These panes are arranged in suitable grooves in the 70 sides of the frame, and the latter is arranged at both ends so the colored-signal panes and the panes bearing the inscriptions can be easily slipped into place, these inscriptions 75 denoting the route or destination of the car 80 or any other matter or suitable advertisement which is desired to be displayed to the public.

Our invention comprises more explicitly the constructions and combinations of parts, 85 which are hereinafter described, and more particularly set forth in the claims.

In the drawings accompanying this specification we have illustrated several of the possible embodiments of our invention, and 90 wherein—

Figure 1 is a front elevation of one form of an electrically-illuminated four-sided sign embodying our invention. Fig. 2 is a plan of the same, having the translucent sign, the 95 bull's-eyes, and colored plates of the top side removed, so as to disclose the interior. Fig. 3 is a front elevation of the sign, showing in position a protecting-hood which may be employed in connection with the sign. Fig. 100 4 is an end elevation of the form shown in Fig. 1 of the end carrying the actuating mechanism. Fig. 5 is an end elevation of the same of the opposite end to the actuating mechanism. Fig. 6 is a transverse section 105 of the signal-compartment, taken on the line A B of Fig. 1. Fig. 7 is a section of the side of the signal-compartment, taken on line

G H of Fig. 2 and showing the manner of holding the bull's-eyes and colored panes. Fig. 8 is a transverse section of the sign-compartment, taken on the line C D of Fig. 2 and showing the method of supporting additional lamps, if necessary. Fig. 9 is an elevation of the actuating mechanism and locking device. Fig. 10 is a bottom view of the upper locking-disk, and Fig. 11 is a plan of the locking-disk fixed to the shaft. Fig. 12 is a plan of the hand-wheel. Fig. 13 is a cross-section of this hand-wheel, taken on the line E F of Fig. 12 and showing one of the ways of holding the removable brass name-plates. Fig. 14 is a cross-section of the same, taken on the line I J of Fig. 12. Fig. 15 is a perspective view of the weather-hood. Fig. 16 is a diagram of connections, showing a possible form of wiring. Fig. 17 is a diagram of connections, showing an alternate form of wiring. Fig. 18 is a pictorial representation of the connections as shown diagrammatically in Fig. 16. Fig. 19 is a cross-section on line I J of Fig. 1, showing the lug and fixed disk of the clutch in the locking device.

Referring now to Figs. 1, 2, 3, 4, and 5, it is seen that the complete sign may consist of a four-sided box with separate compartments, one of which is the sign proper, while the other compartments comprise the signals. The frames 25 of this box are made of strips of suitable material, preferably sheet metal, and held in place by the end and partition pieces 26, made of blocks of wood or other suitable material. The metal frames 25 are properly grooved, so as to form slides for holding the panes 27, made of glass, celluloid, or any suitable translucent material and bearing any desired inscription, illuminated by the lamps 40 in this compartment. The lamps 39_a and 39_b are in the signal-compartments, whose sides are preferably metal plates 28, carrying clear-glass bull's-eyes 29 and held in place each side by four screws 30. The entire box is supported by the standards 31, one at each end, and is mounted so as to be revolved or reversed at will by turning the hand-wheel 32. Thus by rotating the rod 33 and the bevel gear-wheel 34, which engages with the bevel gear-wheel 35, mounted on the shaft supporting the box, the latter is caused to rotate. The brushes or springs 36_a, 36_b, 36_c, and 36_d are for the purpose of making electrical connection to the wiring that feeds the lamps 39_a, 39_b, and lamps 40. These brushes or springs are screwed to the vertical faces of the blocks of hard fiber 38, so as to bear on the metal rings 37_a, 37_b, 37_c, and 37_d, respectively, which in turn are connected to the wiring on the interior of the sign-box by the stud-bolts 55_a, 55_b, 55_c, and 55_d, passing through the sides 26. The entire box, standards, actuating mechanism, and brushes or springs are mounted on a wooden base 41, which is fas-

tened to the roof of the car by bolting down the iron supports 42. This base and the supports can of course be omitted, if desired, and the other parts fastened directly to the roof of the car.

Figs. 6 and 7 show in detail the construction of the signal - compartments. The metal strips 25 form the frames and are U-shaped, so as to form slides in which the colored panes 43, of red, blue, or yellow glass, celluloid, or any suitable translucent colored material, can be inserted. These are held in place by screws 30, which at the same time fasten on the metal sides 28, each one of which carries a clear - glass bull's - eye 29. The lamp 39_a, in section, and its socket are shown in the center of Fig. 6.

Fig. 8 shows in detail a method of supporting any lamps not fastened directly to the partitions or to the ends of the box. One or two sockets are screwed to a piece of wood 44, circular or of any other suitable shape, which is supported by through - bolts 45, passing diagonally from the frames 25, that form the edges of the box and also the slides for the panes 27, carrying the inscriptions to be displayed.

Figs. 9, 10, 11, and 19 give in detail the actuating mechanism and the locking device. The vertical rod 33 carries a bevel gear-wheel 34, engaging with another bevel gear-wheel 35, fixed to the shaft of the box, thereby causing the sign to make one complete revolution for one revolution of the vertical rod 33, which also has fixed upon it the lower locking-disk 48, carrying four wedge-shaped grooves 49, arranged radially ninety degrees apart. The upper locking-disk 46 has a diametral wedge-shaped projection 47, which fits into the grooves of the lower disk 48. Ordinarily the two disks are pressed together by the pressure of the spring 56, and as the upper disk 46 cannot be rotated, but is fixed in position, because the lug 57 engages in a vertical slot in the standard on that end of the sign, accidental rotation of the sign is prevented, because the sign-box is always left in such a position that the projection 47 of the upper disk 46 fits in the groove 49 of the lower disk 48, thereby keeping the lower disk 48 and the sign-box in a fixed position. By forcibly rotating the vertical rod 33 the upper disk 46 is forced upward, overcoming the pressure of the spring 56, so the lower disk 48 can be rotated ninety degrees when the two disks are again locked.

In Figs. 12, 13, and 14 are shown the details of the hand-wheel 32 and name-plates 51, used to enable the conductor or motorman to tell the position of the overhead sign. The hand-wheel 32 has four spokes 50, to which the name-plates 51, of brass or any other suitable material, can be fastened by shaping them as shown, slipping one end of each into one of the grooves 58 and then fas-

tening to one of the spokes 50 with one of the screws 52. The entire wheel is fixed to the vertical rod of the actuating mechanism in such a manner that the names on the spokes 5 have a definite position when the overhead sign shows a particular inscription.

Fig. 15 shows the metal weather-hood, which is fastened by hinges 53 either to the wooden base carrying the sign or directly to the roof of the car, in case no base is employed, in which case the lowest edges of the hood must be given the proper curvature instead of being straight lines. The hood is composed of two plane end surfaces perpendicular to the axis of the rotating sign and two curved surfaces whose elements of surface are straight lines parallel to the axis of the rotating sign. The front face is composed of two curved pieces 54, extending from the end surfaces toward the center, but leaving an opening in the center of sufficient size to leave the signals and sign uncovered. This construction practically entirely incloses the standards, the brushes or springs, and the collector-rings at the ends of the rotatable box when put in place, thus protecting them from the weather and yet leaving these parts accessible for inspection by merely laying the hood back.

Figs. 16 and 18, respectively, give a diagram of the wiring and show the arrangement and connections of the various devices applicable to two signs like the one represented in Fig. 1 and show how the signals and the signs proper can be controlled separately. Starting from the trolley-pole T a wire 58 is led to a make-and-break switch S₁, from which the circuit passes through R₁, which is a rheostat, lamp, or other suitable resistance depending upon the voltage of the trolley-circuit, the number and kinds of incandescent lamps employed, and their method of connection. From R₁ the circuit passes by a wire 59 to the brush 36_a, bearing on the collector-ring 55_a. The incandescent lamps 39_a and 39_b are the signal-lamps in the end or signal compartments and are connected in series between the collector-rings 55_a and 55_b. Collector-ring 55_a has bearing upon it brush 50 or spring 36_b, which is connected by wire 60 to brush 36_a' at the other end of the car. From brush 36_a' the circuit passes by way of collector-ring 55_a', lamps 39_a' and 39_b', in their signal-compartments, collector-ring 55_b', brush 36_b', and then by wire 61 to the rail. A second circuit starts again at trolley-pole T and passes by wires 62 and 63 through R₂, which is another rheostat, lamp, or suitable resistance, to a double-throw switch S₂, which 60 according to its position causes the sign-compartment at the front or at the rear end of the car to be lighted. Wire 64 then connects one terminal of this switch to brush 36_c, bearing on collector-ring 55_c, from whence the 65 circuit passes through as many lamps 40 as

there are in the sign-compartment and passes out by collector-ring 55_d, brush 36_d, and wire 66 to the rail. Wire 65 connects the other terminal of switch S₂ to brush 36_c', bearing on collector-ring 55_c', and thus through 70 lamps 40', which are in the sign-compartment at the opposite end of the car, to collector-ring 55_d', brush 36_d', and by wire 67 to the rail.

Fig. 17 gives a diagram of wiring applicable to two signs similar to one shown in Fig. 3 and keeping the signals always lighted no matter which sign is illuminated. Starting from the trolley-pole T', a wire is led to a make-and-break switch S₁', from which the 75 circuit passes through R₁', which is again a rheostat, lamp, or other suitable resistance, and then by a wire 69 to the brush or spring 36_a'' bearing on collector-ring 55_a'', thence through lamp 39_a'', which is a signal-lamp, 80 to collector-ring 55_b'', brush 36_b'', and by wire 70 to the opposite end of the car and to brush 36_a''' and collector-ring 55_a''', thence through signal-lamp 39_a''', collector-ring 55_b''', brush or spring 36_b''', and by way of 85 wire 71 to the three-way switch S₂'. Wire 72 connects one terminal of switch S₂' to brush 36_c''', from which the circuit passes by way of collector-ring 55_c''', lamps 40''', collector-ring 55_d''', brush 36_d''', and wire 73 to 90 the rail. The other terminal of the switch S₂' is connected to the rail through wire 74, brush 36_e''', collector-ring 55_e''', lamps 40''', which are in a sign-compartment at end of car opposite to lamps 40'', collector-ring 55_d''', brush 36_d''', and wire 75.

It is of course understood that the resistances R₁, R₁', and R₂' in Figs. 16 and 17 can be entirely omitted by properly selecting the incandescent lamps in the signal and sign 100 compartments as regards their voltage and changing their number, as required. Again, if storage batteries or any other independent source of electrical energy is employed, the trolley-pole and the wire to rail will be replaced by the main leads from this source.

Having thus described our invention, what we claim as new, and desire to secure by Letters Patent, is—

1. In a device of the class described, a rotatable box having a main compartment therein, removable translucent slides for said compartment bearing the names of stations or routes of cars, two additional end compartments, removable colored translucent 115 slides therefor, electric lamps in all the respective compartments, a pair of metal rings on each end of said box, one pair of said rings being electrically connected with the lamp or lamps in the main compartment, and the other pair with the lamp or lamps in the two end compartments, a spring bearing 120 against each of said rings and connected with a source of electrical supply, means for independently controlling the supply to the 125

lamps of the main and of the end compartments, and means for rotating the said box, substantially as described.

2. In an illuminated sign, the combination of a many-sided rotatable box having a main and two end compartments, as and for the purposes described, electric lamps in all the respective compartments, a rotating mechanism, a locking device, a means of indicating the position of the box, a means of feeding electrical energy continuously to the electric lamps in said compartments, and a means of independently controlling the electrical supply to the lamps of the main compartment and of the two end compartments; substantially as described.

3. In an illuminated sign, the combination of a rotatable box having a main and two end compartments, as and for the purposes described, electric lamps in all the respective compartments, a rotating mechanism, a lock-

ing device, a means of indicating the position of the box, a means of feeding electrical energy continuously to the electric lamps in said compartments, a means of independently controlling the electrical supply to the lamps of the main compartment and of the two end compartments and a removable hood or casing to protect said rotating mechanism, said locking device and said means of feeding electrical energy to the electric lamps from the weather; substantially as described. 25 30

In testimony whereof we have signed our names to this specification in the presence of 35 two subscribing witnesses.

CHAS. W. RYDER.
FRANKLIN ORTH.
